UNITED STATES PATENT OFFICE.

CHARLES NEWTON, OF BUFFALO, NEW YORK.

RIFLE BULLET OR PROJECTILE.

1,096,558.

Specification of Letters Patent. Patented May 12, 1914.

Application filed October 22, 1912. Serial No. 727,113.

To all whom it may concern:

Be it known that I, CHARLES NEWTON, a citizen of the United States of America, and a resident of the city of Buffalo, county of Erie, and State of New York, have invented certain new and useful Improvements in Rifle Bullets or Projectiles, of which the following is a full, clear, and exact description.

10 As is well known to those skilled in the art, a bullet having a comparatively sharp point and driven at a given velocity encounters less air resistance in its passage between the rifle and the object fired at than does one having a less sharp point, and consequently it retains its velocity and energy in a greater measure than does a bullet of the same weight and having a less sharp point.

20 It is likewise well known that a rifle bullet for use upon game at the velocities now in vogue should have a soft point, to the end that it may expand upon impact, tearing and lacerating the animal struck instead of cutting a clean perforation through the animal, since it thus inflicts much greater shock and inflicts death in much less time. It has been found, however, that when the points of the bullets have been 25 made of soft or ductile material, that the extreme sharp point becomes deformed either in transportation, if not carefully packed, or in the magazine of the rifle in which the bullets are used, or in removing them from the magazine to the chamber of the arm. When so deformed the points are generally of an irregular shape and when used in a rifle, they will not fly true and straight.

30 It is further known by those skilled in the art, that when soft and ductile bullets are driven from the rifle at the present high velocities, the point of the bullet becomes considerably flattened, due to overcoming of the inertia of the point of the bullet and when this occurs the velocity of the same is very materially reduced. In producing my invention, I have therefore, sought to provide a bullet for rifle fire arms, the exposed 45 point of which shall be made of very soft and ductile material so as to gain every possible advantage derived from the expansion and spreading of the bullet upon impact and also to provide a support for the point of said bullet which will prevent it from becoming deformed through transportation

or when in use in the magazine of the gun, or in being transferred from the magazine to the chamber of the gun. Furthermore, I have sought to provide a support for the exposed end of the bullet which shall keep the soft or ductile metal in the exposed point in its original pointed form when being fired from the gun, so as to prevent flattening of the point.

45 Reference is to be had to the accompanying drawings forming part of this specification, in which like characters of reference indicate like parts, throughout the several views of which:

50 Figure 1 is an enlarged side elevation of a bullet partly in section which is provided with a straight center support of harder metal. Fig. 2 is a similar view of a modified form of my bullet. Fig. 3 is a sectional elevation of a fragmental portion of my bullet. Fig. 4 is a side elevation of a fire arm cartridge showing the bullet projecting from the forward end.

55 Referring to the figures and more particularly to Figs. 1 and 4, 5 represents the cartridge with which my bullet is used and 6 the bullet thereof. The bullet 6 is formed of a body 7 of ductile material such as lead, which is inclosed within a casing or jacket 8 extending forwardly and terminating at a short distance from the forward end 9 of the bullet.

60 10 is a central support which is made of harder metal than the bullet. This support 90 is disposed in the center of the bullet and extends out to the extreme point of the end 9 thereof.

65 In Fig. 2, where I have shown a modified form of my invention, a central support 11 95 of harder metal than the bullet is disposed on a line with the axis of the bullet and the forward end thereof extends to the extreme point of the end 9 of the bullet. This central support is designed to prevent the bullet from flattening on the point when being fired from the gun and it is preferably formed with a plurality of cylindrical steps 12, increasing in diameter from the point to the rear end and with a tapered base 16 100 as shown, whereby a series of shoulders or supporting ledges 13 are formed. Obviously, if desired, the tapered end portion 16 may be dispensed with, leaving the base flat. When the tapered base is used, the 110 bullet has greater expanding properties than when the flat base is used.

In Fig. 3, I have shown a central support 14 for the same purpose as that shown, in Fig. 2. In this figure the support is formed of a harder material and disposed on a line 5 with the axis of the bullet and extends out to the extreme point thereof. This support is provided with a plurality of tapered collars 15, having their forward faces at right angles to the axis of the bullet, thus forming 10 supporting surfaces for the metal in the point of the bullet, so as to prevent the same from flattening when being discharged from the gun. Obviously, substantially the same advantages may be obtained by making the collars 15 in spiral form in place of the concentric collars shown.

It will be seen that with a bullet formed according to my invention, the body of the bullet may be made of any material having 20 the desired ductility and that when so constructed, it will be protected against deformation as well as flattening at the point and will thus always fly true when discharged from the gun.

25 Having thus described my invention, what I claim is:

1. A bullet comprising a sharp pointed body of ductile material, a central pointed support of comparatively hard material disposed in said body and extending to the extreme outer pointed end thereof, and a casting of stronger material enveloping said body, except at its forward pointed end where the ductile material is exposed for a 30 short distance backward from such end, whereby the bullet will expand on impact.

2. A bullet comprising a sharp pointed body of ductile material, a central pointed support of comparatively hard material disposed in said body and extending to the extreme outer pointed end thereof, said support being provided with a plurality of shoulders facing the pointed end of said body and disposed at substantially right 40 angles to the axis of the bullet, and a casting of a stronger material enveloping said body, except at its forward pointed end 45

where the ductile material is exposed for a short distance backward from such end, whereby the bullet will be prevented from 50 becoming accidentally deformed without interfering with its expansion on impact.

3. A bullet comprising a sharp pointed body of ductile material, a central pointed support of comparatively hard material disposed in said body and extending to the extreme outer pointed end thereof, said support being formed with a plurality of cylindrical steps, each step being larger in size than the preceding one, starting at the 60 point, thereby forming a plurality of shoulders facing the said point, said shoulders being disposed at substantially right angles to the axis of the bullet, and a casting of a stronger material enveloping said 65 body, except at its forward pointed end where the ductile material is exposed for a short distance backward from such end, whereby the bullet will be prevented from becoming accidentally deformed without 70 interfering with its expansion on impact.

4. A bullet comprising a sharp pointed body of ductile material and a central pointed support of comparatively hard material disposed in said body, and extending 75 to the extreme outer pointed end thereof, said support being formed with a plurality of cylindrical steps, each step being larger in size than the preceding one, starting at the point, thereby forming a plurality of 80 shoulders facing the said point, said shoulders being disposed at substantially right angles to the axis of the bullet, said support being provided at its inner end or base with a tapered portion, whereby the spreading 85 properties of the bullet upon impact with a resistive body are increased.

In testimony whereof, I have hereunto signed my name in the presence of two subscribing witnesses.

CHARLES NEWTON.
